UNITED STATES PATENT OFFICE.

GEORGE W. WHITE, OF WACO, ASSIGNOR TO THE TEXAS FIRE-CLAY MANUFACTURING COMPANY, OF FORT WORTH, TEXAS.

FLUID-BURNER FIRE-LOG.

SPECIFICATION forming part of Letters Patent No. 398,920, dated March 5, 1889.

Application filed December 11, 1888. Serial No. 293,294. (No model.)

To all whom it may concern:

Be it known that I, GEORGE W. WHITE, a citizen of the United States, residing at Waco, in the county of McLennan and State of 5 Texas, have invented certain new and useful Improvements in Fluid-Burner Fire-Logs; and I do hereby declare the following to be a full, clear, and exact description of the invention, such as will enable others skilled in 10 the art to which it appertains to make and use the same.

My invention relates to fluid-burner fire-logs adapted to be placed in fire-chambers of furnaces, stoves, boilers, brick-kilns, fire-places and grates, or in any other fire-chamber, for warming buildings, generating steam, burning brick, cooking, and smelting ores and products thereof; and it consists in the novel construction of portable fluid-burner fire-logs, 15 as hereinafter described and specifically claimed.

In the accompanying drawings, Figure 1 is a vertical longitudinal section of my improved fluid-burner fire-log with the fluid-supply and 20 the air-induction connections thereof. Fig. 2 is a vertical transverse section of the same, looking toward the supply and the air-induction connections. Fig. 3 is a vertical longitudinal section of my fire-log applied 25 to a locomotive-boiler. Fig. 4 is a horizontal section of a brick-kiln with my invention applied to it at two ends; and Fig. 5 is a longitudinal section on a reduced scale, showing a 30 modification of the invention.

A in the drawings represents the tubular body of the fluid-burner fire-log, which in cross-section may be in the form of a circle, ellipse, ovate, polygon, or any other suitable geometrical figure. This body is constructed 35 with open ends and with burner or jet perforations *a* in its periphery along nearly its entire length and partly around or nearly over its circumference, as circumstances or the use of the log may require. The open-ended body portion A is closed at its ends by strong asbestos-packed flanged metallic heads A' A², the flanges *a'* *a'* of which overlapping and encircling the ends of the said body and the edges of the asbestos packing-sheets A³, as shown. 40

Through each of the heads a perforated tube, B, for conduction and distribution of

the fluid fuel, is inserted, and on the ends of this tube screw-threads *b* *b'* are cut, and upon these threaded portions nuts *c* *c'*, packed with asbestos, as shown, are applied outside the 55 heads. While the tube B serves as a distributor and conductor of the fluid, it, with the nuts *c* *c'*, serves also as a means for tying the heads and body A together. Another perforated tube, C, having screw-threads *b*² *b*³ and 60 packed nuts *c*² *c*³ at its ends, is passed through the heads A' A² and made to serve as a tie between the body A and the heads, same as the tube B, while it also serves the purpose of conducting and distributing air for insuring air at 65 the jet-passages of the fluid-burner fire-log. The tube B is perforated, preferably, only on top with one, two, or more rows of jet-passages, *d*, while the tube C is preferably perforated all round or over its circumference with air-inducting passages *f*, and the tube B is placed in about the same vertical plane with the tube C, some distance above it, as shown.

Within the fire-log structure asbestos, in a comminuted or disintegrated condition, is 70 placed so as to completely fill the jet-passages and chamber formed and inclosed by the body A and heads A' A², and also surround the fluid-supply tube and air-induction tube, as 75 illustrated at M in the drawings. The asbestos, while placed quite compactly in the fire-log, forms numerous capillary passages for the regular and proper flow of the fluid through it to the jet-passages, and also for the circulation of air for insuring combustion of 80 the fluid at said jet-passages.

The pipe B is connected with a supply-pipe from the fluid-supply reservoir by means of a coupled vertical pipe, B', as shown, and the air conducting and distributing pipe C is connected with a vertical coupled air-supply pipe, C', as shown, and the vertical pipes B' C' are provided, respectively, with a cut-off and regulation cock, as indicated at B² C². 85

At the upper end of the air-supply pipe C' 90 a funnel-shaped mouth-piece, C³, is provided, and this may be fitted so as to be turned to the wind as occasion may require. In the drawings by Fig. 4 I have shown the manner in which a series of fluid-burner fire-logs may 95 be applied in the eyes of an ordinary brick-kiln, as D, and the series connected by a 100

transverse pipe, B³, adapted for forming communication with the main supply-pipe of the oil-supply reservoir B⁴ and with a series of vertical coupled pipes similar to that B'. In 5 this use of the invention the air-supply pipes will all have a funnel-shaped mouth-piece, as C³, adapted to be turned to the wind, and when so turned strong currents of air will be forced down the pipes into the fire-log, and 10 to the burning of the oil at the jet-passages will be very perfect, and the flames produced will be forced with great energy away from the jet-passages and whirled in great burning volumes into the arches and amid the stacks 15 of brick, thus effecting the burning of the brick in a shorter time and in a more uniform manner than heretofore with ordinary arrangements for burning.

In Fig. 3 of the drawings I have illustrated 20 the manner in which the invention may be applied to the fire-chamber of a locomotive-boiler, E, and on the air induction or supply pipe C' a funnel-shaped mouth-piece, C³, is provided. With this arrangement the air is 25 forced by the motion of the locomotive down the pipe into the fire-log, and while the combustion at the jet-passages is insured the whirling of the flames produced along the flue or flues of the boiler is accomplished and 30 a greater amount of effective heat from a given amount of fuel is secured. In the manufacture of my improved fluid-burner fire-logs I may employ either metal or fire-clay bodies A; but it is preferable to make the 35 body portion A of fire-clay or equivalent argillaceous material, because such material is fire-proof, enduring, and not liable to corrosion, and in connection with this fire-clay tube it is preferable to employ strong cast-iron 40 heads with binding end flanges and asbestos or other fire-proof protection-packing at the joints between the body and the head and where the nuts are applied on the pipes, so as to make the joints oil-tight, and in order to 45 thus use a clay tube or cylinder and cast metal heads means for binding the same together must be provided, and such means are very conveniently and economically secured by my hereinbefore-described mode of extending 50 the perforated pipes B and C through and beyond the heads A' A², threading said extended ends, and applying nuts thereon for binding the heads and body together, and at the same time securing the pipes in their 55 proper positions. By having the heads removable, whether the body portion is made of clay or metal, the filling of asbestos or other equivalent fire-proof material can be conveniently introduced into the chamber of the fire- 60 log, and by employing two fire-proofs materials in the construction of the fire-log—to wit, fire-clay and asbestos—great saving is effected, for there will be very little expense after a stove, grate, furnace, locomotive, or kiln has 65 once been equipped with such logs, while a further greater saving will be effected in cost for fuel consumed, as coal-oil or petroleum

employed in connection with my logs is found very effective and economical for the various uses mentioned and far preferable to other 70 fuels, the smoke being consumed and sparks and cinders avoided. I prefer making the logs for fire-places, stoves, and grates with flattened bottoms, as they maintain their position better when of that form than when 75 round; but the form is immaterial. The logs may be perforated all round when set above the bottom of the furnace or kiln. When the logs are small and used for stoves and grates, the air-pipes may be left off; but this would 80 not be a departure from the principle of my invention, as the fire-log formed of a tubular body portion, preferably of fire-clay, metal heads, perforated oil and tie tubes, and the asbestos filling constitutes one leading feature, 85 and the addition thereto of the air induction and distributing tube another important feature of invention.

My portable fire-log is adapted for application to locomotives, brick-kiln, and other furnace chambers, and can be removed for repair or other purpose without disturbing the fire-box and other parts of such structure. I contemplate as a modification of my invention to cut off the inner extension of the oil-supply tube and to close the opening in the head through which the end of said extension passes, and to fill the space which said extension, if used, would occupy with asbestos, as illustrated in Fig. 5. With this construction 90 the comminuted asbestos alone would be the means for conducting the oil to the jet-burner passages. I, however, prefer to employ the perforated tie-tube for conducting and distributing the oil, as the same is much the best 95 mode.

It will be understood from the foregoing description and accompanying drawings that it is essential that the body portion of my fluid-burner fire-log shall be made of strong 100 rigid material—such as fire-clay or heavy cast or wrought metal—and that the heads shall be of strong rigid material—such as cast or wrought metal—in order that the fire-log may be enduring and capable of withstanding the 105 great and continuous heat of fires such as are required for running brick-kilns, locomotive, and boiler furnaces; also to be adapted for constant use as a substitute for fuel—such as coal and wood—in stoves, heaters, and fire- 110 places.

It will further be seen that the perforated oil-distributing tube or air-distributing tube, or both tubes, require to have strong screw-threads cut upon their ends; that such ends shall extend both outside the heads and have strong nuts applied thereon, so that the heads and body portion of the log can be bound strongly together, which binding of the said parts is enhanced by providing strong overlapping flanges on the heads. It will be further seen that there is a great advantage in the saving of expense, as well as utility, in providing for both distributing the oil and 115 120 125 130

supplying, distributing, and forcing the air by means of perforated tubes, which also serve as tie-tubes between the heads and the body of the fire-log.

5 It will further be seen that it is very important to surround both the oil-distributing and the air-distributing tubes with comminuted asbestos and to pack the joints with sheets of the same material, as this substance is fire-
10 proof and affords every facility for the circulation of the air and fluid or oil.

My invention in the construction and form of its parts, the proportions or thickness and strength thereof, and the purposes and uses
15 for which it is designed would be of no practical use as a fire-kindler; nor would fire-kindlers nor vapor-burners, &c., constructed as in Letters Patent Nos. 373,465, 196,613, 31,466, 135,011, and 252,014 be capable of practically and usefully serving the purposes for
20 which my invention is intended.

What I claim as new, and desire to secure by Letters Patent, is—

1 A portable fluid-burner fire-log having,
25 in combination, a perforated tubular body, metallic removable heads, a fluid-supplying tube, a perforated air-induction distributing tie-tube provided with screw threads and nuts on its ends outside the heads, and a comminuted
30 or disintegrated fire-proof filling surrounding the perforated portion of the air-tube and occupying the chamber of the body, substantially as and for the purpose described.

2. A portable fluid-burner fire-log having,
35 in combination, a perforated tubular body,

metallic removable heads, an air-supply tube, a perforated fluid-conducting and distributing tube provided with screw threads and nuts at its ends outside of the heads, and a comminuted fire-proof filling surrounding the 40 perforated portion of the oil-tube and occupying the chamber of the body, substantially as and for the purpose described.

3. In a portable fluid-burner fire-log, the combination of the perforated tubular body, 45 metallic removable heads, a perforated oil conducting and distributing tie-tube, a perforated air induction and distributing tie-tube, both of said tubes provided with screw threads and nuts on their ends outside of the heads, 50 and comminuted or disintegrated fire-proof filling surrounding the perforated portions of the tubes and occupying the chamber of the body, substantially as and for the purpose described.

4. In a portable fluid-burner fire-log, the combination of the perforated body, the removable heads, the perforated tie and oil induction and distributing tube, air supply and distributing tube provided with an inner perforated portion and an imperforated outer portion with funnel-shaped mouth, and a fire-proof filling, substantially as and for the purpose described.

In testimony whereof I hereunto affix my 65 signature in presence of two witnesses.

GEORGE W. WHITE.
